UNITED STATES PATENT OFFICE.

DELBERT E. JOHNSON, OF OTTUMWA, IOWA.

TRACK-LAYING APPARATUS.

SPECIFICATION forming part of Letters Patent No. 399,048, dated March 5, 1889.

Application filed March 16, 1887. Serial No. 231,183. (No model.)

To all whom it may concern:

Be it known that I, DELBERT E. JOHNSON, a citizen of the United States, residing at Ottumwa, county of Wapello and State of Iowa, have invented a new and useful Improvement 5 in Track-Laying Machines, which I desire to protect by Letters Patent of the United States, of which the following is a specification.

My present invention relates to the class of 10 machines previously patented to me in Letters Patent of the United States No. 354,146, dated December 14, 1886; and it consists in certain improvements, hereinafter specifically pointed out and claimed.

15 In the drawings hereto annexed and forming part of this specification, Figure 1 is a perspective view of an engine and several cars of a train to be used in track-laying and to which my invention has been applied. Fig. 2 is a plan view of a part of the tie-delivering conveyer. Fig. 3 is a side elevation of the same. Figs. 4 and 9 are details of the bracket supporting the conveyer and attached to the car and Figs. 5, 6, 7, and 8 are views of several forms of a flexible coupling used in the pipe connecting the engine which propels the conveyer with the locomotive-boiler.

Heretofore it has been usual to use a stationary engine and boiler located upon one of the cars of the track-laying train to propel 30 the automatic delivery apparatus, which forms the principal subject-matters of the aforesaid patent. I find that a considerable economy of force can be had by using a stationary engine merely and propelling the same from the boiler of the locomotive used for propelling the cars, thus dispensing entirely with the stationary boiler. I am thus 35 enabled to utilize the blow-off steam from the engine and to propel my automatic tie-carrying apparatus without the use of extra fuel.

In order that the pipe-connection between the stationary engine and the boiler of the locomotive may not be disarranged by the 40 relative motion of the engine and the car upon which the stationary engine is located, it is desirable to provide some sort of a flexible or yielding connection in the aforesaid pipe between the engine and the car.

45 In the drawings the cylinder of the stationary engine is represented at A and connection is made with the locomotive-boiler by

means of the pipe B. Connection between the two parts of the pipe B, attached respectively to the car and the locomotive, is made 55 by a flexible hose or other yielding connection of any appropriate or suitable form, a number of such forms being shown in Figs. 5, 6, 7, and 8. Fig. 5 represents the usual flexible hose-connection—such as is used in the West- 60 inghouse air-brake system, and which can be applied to my invention.

C is a section of rubber hose, one end of which is attached to the pipe B on the engine, and the other end to a metal coupling, D. C' 65 is another section of rubber hose connected at one end to the said coupling D and at the other to the section of pipe B upon the car carrying the stationary engine.

In Fig. 6 a modified construction is shown, 70 in which a casing, E, provided at one end with a rubber packing, F, is united by a screw threading with one of the pipes B and receives at the other end the other pipe B, the rubber packing F preventing escape of 75 steam. A further modification is shown in Fig. 7, in which a simple section of hose, G, connects the two sections of pipe B. In Fig. 8 a further modification is shown, in which the two sections of pipe B are connected by 80 a metallic pipe, H, adapted at one or both ends to swing in joints I.

A further improvement upon my former patent consists in the construction of the bracket used for supporting the conveyer. 85 (Shown particularly in detail in Figs. 4 and 9.) This is adapted for use with the ordinary pockets K, attached to the sides of freight-cars, and consists of an upright, L, on which is cast a block, M, of a size approximately 90 fitting the pocket. To this upright L is pivoted at its top a cross-piece, N, provided at its outer end with an upwardly-projecting lug, O. To this outer end is pivoted a diagonal post, P, the lower end of which has a 95 tenon, P', which takes into a slot in the lower end of the upright L, the lower end of this upright being bent outward to more readily receive this tenon. When in position the entire weight of the structure rests upon the 100 upper outer edge of the pocket, the lower part of the upright L being so placed, as shown, as to bear against the side of the car, thus preventing the tipping of the bracket.

under the weight of the conveyer. This construction of bracket is very simple, and has the advantage of ready application to and detachment from the car, it being only necessary to raise the post P out of its socket and lift up the cross-piece N to raise the entire bracket out of the pocket. The upper end of the upright L being continued above the cross-piece forms a lug, which, with the lug 10 O, prevents lateral displacement of the framework of the conveyer upon the bracket. This conveyer frame-work is shown in section in Fig. 4 at 2. In order to prevent lateral movement of the conveyer, it is desirable to provide lugs R upon the side strips of the frame on both sides of one or more of the brackets.

I have found in practice that the roller S, upon which the ties travel, when made, as shown herein, of cross-strips T, connecting 20 two heads, V V', is not sufficiently durable, for the reason that the strips T are likely to become bent. In order to give the roller greater strength I propose to support the strips at their centers by means of an interior 25 hoop, U.

I wish it understood that I do not limit myself to the particular form or construction of any of the parts shown, but claim, broadly, all the equivalents of those constructions. 30 Neither do I limit myself to the use of any one or more of the various improvements shown, but claim each feature by itself and without reference to any other features shown.

Having thus described my invention, what I 35 claim, and desire to protect by Letters Patent, is—

1. In a track-laying apparatus, the combination of a locomotive-engine, a conveyer, an engine for propelling the conveyer supported 40 by one of the cars of the train, and a pipe-connection between the locomotive-boiler and

the engine aforesaid for propelling the conveyer, substantially as set forth.

2. In a track-laying apparatus, the combination of a locomotive, a conveyer, a separate 45 engine for propelling the same, and a pipe-connection between said separate engine and the locomotive-boiler, said pipe-connection being provided with a yielding coupling for permitting the pipe to accommodate itself to 50 relative movements of the locomotive and the car, substantially as set forth.

3. In a track-laying apparatus, the combination of a locomotive-engine, a conveyer, a 55 separate engine for propelling the same, a pipe-connection between said separate engine and the boiler of the locomotive, and a flexible hose-connection between the parts of said pipe attached, respectively, to the locomotive and the separate engine, substantially as set 60 forth.

4. In a supporting-bracket for conveyers in a track-laying apparatus, the combination of an upright to pass through and extend below the stake-socket and approximately fitting 65 the opening of said socket, a cross-piece pivoted at one end to the top of said upright above the socket, and a diagonal brace pivoted at one end to the outer end of said cross-piece, and its lower end having a bearing in 70 the lower end of the upright, substantially as described.

5. In a track-laying conveyer, the combination of a frame-work for supporting rollers, a bracket, and lugs attached to said frame-work for preventing lengthwise motion thereof 75 in the brackets, substantially as set forth.

DELBERT E. JOHNSON.
